[57] CLAIM

The ornamental design for an environmentally sealed insulation displacement connector terminal block, as shown and described.

DESCRIPTION

FIG. 1 is a perspective view of an environmentally sealed insulation displacement connector terminal block showing our new design;

FIG. 2 is a front elevational view thereof;

FIG. 3 is a left side elevational view thereof;

FIG. 4 is a right side elevational view thereof;

FIG. 5 is a top plan view thereof; and,

FIG. 6 is a bottom plan view thereof.

The rear elevational view thereof is not the result of ornamental considerations and contains no ornamentation.

FIG. 2

FIG. 3

FIG. 4
